DESIGN FOR AN ELECTRIC SIGN

Clarence E. Karst, Cincinnati, Ohio, assignor to
The Brunhoff Manufacturing Co., Cincinnati,
Ohio, a corporation of Ohio

Application April 19, 1937, Serial No. 68,859

Term of patent 3½ years

To all whom it may concern:

Be it known that I, Clarence E. Karst, a citizen of the United States, residing at Cincinnati, in the county of Hamilton and State of Ohio, have invented a new, original, and ornamental Design for an Electric Sign, of which the following is a specification, reference being had to the accompanying drawing, forming a part thereof.

The figure is a perspective view of an electric sign, showing my new design.

I claim:

The ornamental design for an electric sign, substantially as shown.

CLARENCE E. KARST.
